UNITED STATES PATENT OFFICE.

OLMEDO CORTEZ WYSONG, OF GREENSBORO, NORTH CAROLINA; FANNIE I. WYSONG
EXECUTRIX OF SAID OLMEDO CORTEZ WYSONG, DECEASED.

BED-RAIL.

1,333,008.

Specification of Letters Patent.

Patented Mar. 9, 1920.

Application filed October 3, 1917. Serial No. 194,491.

To all whom it may concern:

Be it known that I, OLMEDO CORTEZ WYSONG, a citizen of the United States, and a resident of Greensboro, in the county of 5 Guilford and State of North Carolina, have invented a new and useful Improvement in Bed-Rails, of which the following is a specification.

My invention relates to improvements in 10 furniture, and it consists in the constructions, combinations and arrangements herein described and claimed.

An object of my invention is to provide a 15 bed rail, the principal feature of which lies in extensible blocks adjustably mounted in the extremities of the rail, by the use of which the length of a bed may be increased.

Another object of the invention is to provide a bed rail in which the main body portion 20 is metallic, blocks carrying bed hooks being adjustably mounted in the extremities of the metallic rail, said blocks having adjustable tie-rods by the use of which the bed rails are prevented from spreading.

Another object of the invention is to provide a crimped or fluted bed rail having 25 blocks bearing bed hooks, inserted in the ends, said blocks being susceptible to adjustment if desired.

Another object of the invention is to provide a metallic bed rail as described, with spacer blocks for preventing rattling and the giving of metallic sound upon striking the bed rail.

Other objects and advantages will appear 30 in the following specification, reference being had to the accompanying drawings, in which:

Figure 1 is a side elevation of a bed rail 40 showing the adjustable blocks, and the tie-rods in a nested position.

Fig. 2 is a side elevation of a bed rail showing the blocks extended.

Fig. 3 is an enlarged side elevation of a 45 portion of a bed rail showing the extensible block, parts being shown in section.

Figs. 4 and 5 are cross sections on the lines 4-4 and 5-5 respectively, of Figs. 1 and 3.

Fig. 6 is a side elevation of a portion of 50 a bed rail showing the spaced blocks positioned to receive slats therebetween.

Fig. 7 is a plan view showing the arrangement of the tie-rods.

Fig. 8 is a cross section on the line 8-8 55 of Fig. 7.

Fig. 9 is a side elevation showing a modified arrangement for holding one end of a tie-rod.

Fig. 10 is a cross section on the line 10-10 of Fig. 9, and

Fig. 11 is a detail plan view showing a modified adjustment for the tie-rods.

In carrying out my invention I provide a metallic bed rail 1 which is fluted at 2 at the top, and at 3 at the bottom. The flutes 2 are on the outside of the rail 1 and are intended to give the rail a pleasing appearance as well as give it the required strength to bear the weight imposed upon it.

The rail 1 is bent inwardly at 4 at the top 70 and bottom, and then toward the center of the rail as at 5. The ends of the bent portions 5 are then bent toward the body portion 1 of the rail at 6 to provide longitudinal tongues upon which the kerfs 7 of an extensible wooden block 8 slide.

The wooden block 8 fits closely upon the tongues 6 on the extremities of the rail 1 as clearly indicated in the drawing. The block 8 may be adjusted outwardly as shown in 80 Fig. 2. For this purpose the block 8 is provided with a vertical slot 9 in which a bolt 10 is located. The bolt 10 enters a round opening 11 in the top portion 4 of the rail 1, and passes out of a similar opening 12 85 in the bottom portion 4 of the rail 1.

A wing nut 13 is screwed upon the lower threaded portion of the bolt 10. The wing nut 13 is loosened so that the extensible block 8 may be pulled out, whereupon, when 90 the desired adjustment is obtained, the wing nut 13 is again tightened and the block 8 will preserve the position thus obtained by the adjustment. The block 8 has a bed hook 14 which is of a common construction and 95 is intended to hook over suitably arranged pins on the bed posts.

Tie-rods 15 are fixed in a socket 16 of a hinge bracket 17 pivotally mounted upon a hinge block 18 carried by the extensible 100 block 8. The tie-rods 15 are nested in the manner illustrated in Figs. 1 and 2, when the bed rail is shipped. A sleeve 19 is carried upon the ends of the tie-rods 15, and is adjustably fastened by set screws 20.

The nature of the metallic bed rail 1 is such that when it is struck by a glancing blow, a metallic sound will be given, and to obviate this objectionable feature, as well as any rattling which may be caused, spacer 110

blocks 21 are inserted at intervals in the channel formed by the bent portions 4 and 5. One of the spacer blocks 21 is illustrated in Fig. 5. Here it will be seen that each block has a kerf 22 into which the longitudinal tongue 6 enters, similarly as do the kerfs 7 of the extensible block 8.

Attention is directed to Fig. 6. Here it will be seen that the spacer blocks 21 have been moved down a considerable distance so as to leave equal spaces therebetween and engage the side portions of wooden slats 23. The arrangement shown in Fig. 6 is that in an instance where it is desired to use wooden slats instead of a mattress having a metallic frame.

When such a mattress is used, the lugs usually provided, rest upon the support formed at the socket 16 of the hinge member 17. This arrangement is indicated in Fig. 8 where the lug 24 of a mattress having a metallic frame 25 is seen to rest upon the socket 16.

The hinge block 18 is fixed upon the inner vertical face of the extensible wooden block 8. This arrangement positions the hinge member 17 within the channel formed by the bent portions 4 and 5 of the rail 1, when the tie-rods 15 are nested.

30 The tie-rods 15 illustrated more clearly in Fig. 7, form an important feature of the invention. It will be seen that each of the tie rod members is carried by one of the wooden blocks 8. In setting up the bed, the 35 tie-rods 15 are swung inwardly and the set screws 20 in the sleeves 19 are fixedly adjusted in position. The metallic rail members are thus prevented from spreading. Obviously, a plurality of the tie-rods 15 may 40 be provided intermediate the ends of the rails 1. In other words, another single tie-rod may be put in the middle, or two or three may be employed. The number of tie-rods used is of course, optional with the 45 maker of the bed rail.

Instead of hinging the tie-rods in the manner described above and as shown in the drawings, each tie-rod member 15 may consist of a flat bar having an enlarged head 50 26 on one end. To accommodate this head, an opening 27 is formed in a portion of the wooden block 8, and covered by an escutcheon 28 with a hole 29 into which the head 26 is inserted. The head 26 then rests 55 in the opening 27 as shown in Fig. 10. The tie-rod may be removed by lifting the tie-rod and pulling the head 26 out. An adjustable collar 30 with a wing nut 31, provides for any adjustment necessary to tie-rods 15.

60 It will be of interest to understand the manner in which the use of the extensible blocks 8 came about. These blocks are ordinarily made of oak wood, and are of such proportions that no use other than to use 65 them for kindling wood, can be made of

them. These blocks are a by-product which up to the present time cannot be employed in any useful manufacture.

By running the blocks through an especially designed machine which dresses them, 70 forms the kerfs 7 and the slot 9, I am enabled to employ the by-product referred to, in a useful purpose. By making a metallic bed rail, the interests of cleanliness and sanitation are advanced, and by the use of 75 the blocks referred to, the steps in making a bed rail are very much simplified. The cost of producing the bed rail is very much less than that of producing the common wooden bed rail. In manufacturing the 80 common wooden bed rail, some of the best timber which may be used for other and more useful purposes, is employed.

As an additional preventative to the metallic sounding of the rail which might 85 result upon striking the void flutes 2 and 3, a semi-circular spacer rod 32 is slid into these voids. The spacer rod 32 serves to clamp the spacer blocks even more tightly in position. These rods may, of course, be 90 omitted but are illustrated in the drawing to show how they may be employed if it be desirable to do so.

The blocks 8 are not necessarily extensible. They are put in place at the ends of 95 the metallic bed rail 1 and so clamped by the wing nut 13 and bolt 10, that they will remain rigidly in place or may be extended when it is necessary to do so. The spacer blocks 21 are also by-products similarly 100 employed as are the blocks 8. The spacer blocks 21 are put in place to stabilize the rail, and prevent disagreeable rattling which might otherwise result. The blocks 21 are nailed in position when arranged as shown 105 in Fig. 6.

While the construction and arrangement of the device is that of a generally preferred form, obviously modifications and changes may be made without departing 110 from the spirit of the invention or the scope of the claims.

I claim:

1. A bed rail, consisting of a metallic body, closed on one side and open at the 115 other, bent over at the upper and lower edges to provide channels, and hook-bearing blocks, accessible from the open side, adjustably mounted in the ends of the bed rail between the channels.

2. A metallic bed rail having fluted portions at the top and bottom to strengthen the rail, adjacent bent portions providing tongues at the top and bottom and forming channels, a block partially housed by and disposed at the ends of the rail, with kerfs receiving the tongues, the parts of the block beyond the kerfs occupying said channels, and a fastening element passing through said rail and said block.

3. A bed rail, consisting of a metallic channeled bed rail member, extensible hook-bearing blocks mounted in the channel at the ends of the rail, and spacer blocks occupying the channel preventing said rail from rattling.
4. A bed rail consisting of a metallic sheet bent to form flutes at the top and bottom, the adjacent portions being bent inwardly, downwardly, and again inwardly to provide longitudinal tongues and channels, the upper portions of said rail having coinciding openings on the extremities, a wooden hook-bearing block mounted in the channeled rail at the extremities, said block having a vertical slot coinciding with said openings, a fastening member passing through the said coinciding openings and slot, and spacer blocks carried by said rail with portions located in said channels, said spacer blocks being disposed intermediate the end blocks.
5. A device as described, consisting of complementary bed rail members, hook-bearing blocks mounted with extensible adjustment in the extremities of said rail members, and tie-rods hinged upon said blocks with clamping connections for clamping the rods together.
6. In combination, a bed rail consisting of a sheet metal casing, suitable reinforcements at intervals, held in place by formed parts of the casing, and means held in place by the same parts, at the ends of the casing for connection with the head and foot portions of a bed.
7. In combination, a bed rail consisting of a sheet metal casing, suitable reinforcements at intervals, held in place by formed parts of the casing, means held in place by the same parts, at the ends of the casing for connection with the head and foot portions of a bed, and adjustable securing means passing through vertically for fastening beneath the bed rail.
8. A bed rail consisting of a metallic casing having fluted portions at one side forming voids, and bent portions on the other side forming channels and tongues, hook bearing blocks supported by said casing with portions engaging the channels and tongues, spacer blocks located along said casing with portions engaging the channels and tongues, and longitudinal spacer rods inserted into the flutes occupying the voids and engaging the spacer blocks to assist in preventing the metallic casing from rattling.

OLMEDO CORTEZ WYSONG.
